UNITED STATES PATENT OFFICE

FRANK A. BUCKLAND, OF ROCHESTER, NEW YORK

EXCAVATING MACHINE

Application filed November 5, 1929; Serial No. 405,037;

The present invention relates to digging and excavating machines and has for its object to provide improved means by which to increase the efficiency of machines of this type.

A further object of the invention is to provide improvements in the driving mechanism for urging the buckets or digging implements into the different materials to be operated upon by machines of this type.

A further object of the invention is to provide improvements in the operating and control means for digging implements of excavating machines and the like.

15 A further object of the invention is to provide in a digging or excavating machine of the bucket type, improved means for opening the buckets and for locking them against opening beyond a predetermined position.

20 To these and other ends the invention resides in certain improvements and combinations of parts, all as will be hereinafter more fully described, the novel features being pointed out in the claims at the end of the specification.

In the drawings:

Fig. 1 is a side elevation of an apparatus embodying one form of the invention with the bucket sections shown in open position;

25 Fig. 2 is an elevation of the apparatus shown in Fig. 1 as viewed from the right of this figure;

Fig. 3 is a transverse section taken on line 3a—3a of Fig. 1;

30 Fig. 4 is a view similar to Fig. 1 showing the buckets in closed position;

Fig. 5 is a sectional elevation drawn on an enlarged scale and taken on line 5a—5a of Fig. 1;

35 Fig. 6 is a transverse section taken on line 6a—6a of Fig. 5;

Fig. 7 is a transverse section drawn to an enlarged scale and taken on line 7a—7a of Fig. 4, and

40 Fig. 8 is a fragmentary side elevation of a slightly modified form of bucket support, being means.

Similar reference numerals throughout the several views indicate the same parts.

With the usual type of excavating ma-

chines, the buckets or digging implements are suspended from a boom by a cable and dropped by their own weight against the ground to cause the teeth of the buckets to penetrate the material to be loosened and removed by the buckets. This method of excavating, in many cases, has been found unsatisfactory, and this is particularly true where the machines are used for breaking up and removing various relatively hard and packed materials such as asphalt, gravel and the like.

In the present invention I have provided improvements by which to deliver a rapid succession of blows directly to the buckets or digging implements whereby to avoid the transmission of the driving forces to the buckets through relatively movable parts and from points remote from the buckets. In this way I provide a very practical and efficient digging apparatus in which there is no loss of power between the driving means and the implements themselves. By means of the improvements of the present apparatus, the teeth of the digging implements can, in a minimum amount of time, be made to effectively penetrate the material to be broken or loosened whereby the usefulness and the efficiency of machines of this class is increased to a considerable degree.

Referring to the drawings, the bucket sections are indicated at 10, each of which includes a plurality of teeth or cutting elements 12 suitably secured to a reinforcing member 11 located at the bottom of the bucket. One of the bucket sections is provided with a pair of arms 13 and the opposite section with similar arms 14. Both sets of arms are mounted to swing upon a pivotal support 15 as shown in Fig. 3. A supporting frame for the buckets comprises a head 16 carrying depending elements 17 and 18, the former being shown rigidly connected with the head by a plurality of rivets or bolts 19, while the latter is connected with the head by a pivot pin 20. If preferred both of said elements may be pivotally connected with the head as shown in Fig. 8, in which the left-hand element 17a is a duplicate of the right-hand element 18. At the opposite sides of each of said elements

are parts forming connections for supporting the individual bucket sections. These parts are indicated at 21 and are forked at their lower ends to afford inner and outer bearing members 22 and 23 respectively for receiving the pivot pins 24 which extend through lugs 25 and 26 on a reinforcing member 27 securely connected with the bucket sections, preferably by means of rivets or bolts 28. The parts 21 have their upper ends pivotally secured at 29 to collars 30 sleeved upon the supporting elements 17 and 18 and permitting relative longitudinal movement between the latter and the connections 21. The extent of this movement upon the support 17 is limited in one direction by a stop 31 suitably secured on the support and in the other direction by the head 16, it being understood that the left hand collar 30, Fig. 1, is free to slide vertically between said stops to afford relative movement between the support and the connections 21. Relative movement between the opposite support 18 and the connections 21 thereon is limited by the upper and lower stops 32 and 33 between which the collar 30 is free to slide. In the modification shown in Fig. 8 the stops and movable parts on the support 17a have been given the same reference characters as the corresponding parts on the support 18.

In order to hold the supports and connections in proper alignment under all conditions of operation, the former are provided with longitudinally extending guides 34 for receiving the inner bearing portions 21a of the connections, the guides being preferably in the form of angle bars secured to the support in any suitable manner. The bearing portions 21a terminate short of the upper ends of the connections as indicated at 35 in Fig. 2. The lower ends of the supports are each slidably mounted in a collar 36 preferably formed integral with the bearing portions 21a of the connections and also with the outer side portions thereof by means of a tie member 37, Fig. 2.

Mounted on the pivotal support 15 is a bracket 38 carrying at its upper end a pair of pulleys 39 for receiving the lifting cable 40. The lower end 41 of the cable is suitably connected with the head 16, preferably to a pivot pin 42 supported by the head and on which is rotatably mounted a pulley 43 shown by dotted lines in Fig. 1. The cable is extended downwardly from the head around one of the pulleys 39 and then upwardly around the pulley 43 and back around the other pulley 39, from which it is carried upwardly through the head between two rollers 44, only one of which is shown. The rollers are supported by lugs 45 and 46 carried by the head which is recessed to receive the rollers and other parts. The cable 40 is also extended between a pair of transversely extending rollers 47

and 48 carried by the head above the rollers 44.

The upper end of the cable as will be understood is extended over a pulley on the boom of the excavating machine proper (not shown) and is wound on a power operated drum in the usual manner.

The driving means for the bucket sections is of the fluid pressure operated type and is mounted on the lifting frame which includes the head 16 and the depending supports 17 and 18. The supports are each provided with a piston chamber 49 in which pistons 50 operate to reciprocate the hammer or ram 51 for the purpose of delivering a succession of blows to a portion 52 of the anvil which rests loosely upon a central abutment 53 constituting the remaining portion of the anvil and which is secured on the reinforcing plate 27 of the bucket as best shown in Fig. 5. Steam or compressed air for operating the hammer is admitted to the opposite ends of the chamber 49 through ports 54 and 55 controlled by suitable valves 56 and 57 operating in a valve casing 58 in a well known manner and to which the fluid is admitted under the control of the operator of the machine. The parts 52 and 53 are to be considered as the complete anvil, although they constitute separate elements whereby to permit the bucket sections to swing on the connections 21 while moving to and from closed position.

In the digging operations, assuming that the buckets are in the position shown in Fig. 1, operation of the hammers is begun and at about the same time an upward pull is exerted on the cable 40 to gradually move the buckets toward each other whereby a combined digging and scooping action is afforded. The rapid delivery of the blows of the hammers directly to the bucket sections while the latter are being advanced toward each other serves to insure movement of the same to a sufficient depth to obtain a maximum load in a minimum amount of time.

It will be understood that during operation of the hammers the connections 21 and the supports or cylinders in which the hammers are mounted are free to move longitudinally one with respect to another by reason of the play afforded for the collars 30 between the upper and lower stops on the supports.

Where one of the depending supports or frame members is rigidly fixed to the head 16 as in the case of the support 17 a bracing and steadyng effect is afforded at the point of connection of the bucket with the support and the bucket is thereby more firmly held during penetration of the material to be operated on. This results in a more positive action and a consequent increase in the depth of the cut is afforded. This arrangement is advantageous under certain conditions of operation and particularly where the ma-

chine is used in the breaking up of relatively hard material. Under other or more favorable conditions of operation as when the material to be excavated is relatively soft or loose, it may be preferable to pivotally connect both of the depending supports 18 with the head 16 as shown in Fig. 8.

It has been found advantageous to employ means for positively affording relative movement between the bucket sections to insure opening of the same at the proper time by swinging one relative to the other. I have therefore provided means for this purpose arranged to be power actuated and under the control of the operator of the excavating machine. In carrying out this idea, I provide extensions 59 on the arms 14 of the right hand bucket as best shown in Figs. 3 and 4. Pivoted to each of these extensions at 60 is a lever 61, the levers having their outer ends connected by a transverse member 62 whereby to permit the levers to be simultaneously operated by means of a cable 63 connected with said member. Each extension 59 is provided with a shoulder or abutment 64 and each lever is provided with two angularly disposed portions 65 and 66. When the buckets are in the position shown in Fig. 1 the portion 66 of each lever cooperates with the shoulder 64 of each extension to prevent further opening of the buckets in a manner hereinafter described. With the buckets in the closed position shown in Fig. 4 the portions 65 of the levers engage the abutments 64 of the extensions and it will be seen that if the cable 63 is held and the lifting cable 40 released to lower the buckets, the resultant action will be the opening of the buckets, due to the pressure exerted by the portions 65 of the levers upon the shoulders 64 of the arm extensions 59. In other words, the effect will be the same as if the cable 40 were held while exerting a downward pull on the upper end of the levers by means of the cable 63. The cable 63 is carried around a pulley 67 and upwardly through the head 16 between the lower rollers 44 and the upper rollers 47 and 47a. The cable 63 passes through a lug 68 of the head which forms a stop for a ball-shape member 69 secured to the cable to limit the upward movement of the levers 61. The levers in the position shown in Fig. 1 constitute locking means for holding the buckets to limit the outward movement of the teeth 12 whereby they are held in substantial alinement with the hammers 51 and approximately at right angles to the ground at the beginning of the digging operation.

As stated above the cable 63 is preferably power operated, being extended over a pulley on the boom of the machine (not shown) and wound on a power driven drum under the control of the operator. It will be seen therefore that both cables may be slackened

at the same time or both raised simultaneously and that either may be held and the other released when desired. It will be further seen that the levers 61 function both to open the buckets to effect release of the load 70 and to lock the same against being opened beyond the position shown in Fig. 1.

I claim as my invention:

1. In apparatus of the class described, the combination of a plurality of digging implements, a supporting frame upon which the implements are mounted to swing, an anvil mounted directly on each implement, individual power operated hammers on the supporting frame each arranged to deliver 80 a succession of blows to one of the anvils and means for swinging the implements upon said supporting frame.

2. In apparatus of the class described, the combination of a plurality of digging implements, a frame upon which the implements are mounted to swing, a support pivotally connecting the implements, an anvil directly associated with each implement, individual power operated hammers on the frame 90 each arranged to deliver a succession of blows to one of said anvils and means connected with the support for actuating the same to swing the implements upon the frame.

3. In apparatus of the class described, the combination of a pair of digging implements, a support upon which one of the implements is pivotally mounted for a swinging movement toward and from the other, an anvil directly associated with the implement with 100 which the support is connected, a power operated hammer on said support for delivering a succession of blows to the anvil and means for moving said implements one relative to another.

4. In apparatus of the class described, the combination of a pair of digging implements, relatively movable supports on which said implements are pivotally mounted to swing toward and from each other, an anvil directly associated with one of the implements, a power operated hammer on the support with which the implement having the anvil is connected, said hammer being arranged to deliver a succession of blows directly to said anvil and means for swinging the implements one toward another.

5. In apparatus of the class described, the combination of a pair of pivotally connected digging implements, supports extending upwardly from said implements and upon which the implements are arranged to swing, a fluid pressure operated hammer mounted on one of the supports and arranged to deliver a succession of blows directly to the implement with which the last mentioned support is connected, means connecting the upper ends of said supports and upon which one of the supports is free to swing and means 125

for swinging the implements upon the supports.

6. In apparatus of the class described, the combination of a pair of digging implements, 5 pivotally connected supports for the implements each comprising relatively movable parts on one of which the implements are movable, a power operated driving element for each implement mounted on one of the 10 supporting parts therefor and arranged to deliver a succession of blows directly to the implement, and means for moving the implements relative to said supports.

7. In apparatus of the class described, the 15 combination of a pair of digging implements, parts upon which the implements are mounted for movement one toward another, additional parts connected with the first mentioned parts for movement longitudinally 20 thereof and arranged to have a limited sliding movement thereon, means pivotally connecting said additional parts and means for moving the implements one toward another upon said first mentioned parts.

8. In apparatus of the class described, the combination of a pair of pivotally connected digging implements, supporting devices for the implements each comprising elements having a limited movement one longitudinally 30 of another, means connecting said supporting devices, a power operated hammer on one of the supporting elements for each implement arranged to deliver a succession of blows to the implements and means for raising the supporting devices and the implements connected therewith.

9. In apparatus of the class described, the combination of a pair of digging implements, a pivotal support for the implements, elements 40 extending upwardly from the implements on which they are mounted to swing, additional elements slidably connected with the first mentioned elements and having a limited movement longitudinally thereof, a supporting member for the second mentioned 45 elements on which one of said elements is mounted for a swinging movement, a pulley on said supporting member, a pair of pulleys connected with said pivotal support, a cable having one end anchored upon said 50 supporting member and extending around said pulleys and upwardly from the supporting member, and power operated driving hammers for the implements arranged to be reciprocated on the second mentioned elements.

10. In apparatus of the class described, the combination of a pair of digging implements, a pivotal support for the implements, elements 60 extending upwardly from the implements on which they are mounted to swing, additional elements slidably connected with the first mentioned elements and having a limited movement longitudinally thereof, a supporting member for the second mentioned 65

elements on which one of said elements is mounted for a swinging movement, a pulley on said supporting member, a pair of pulleys connected with said pivotal support, a cable having one end anchored upon said supporting member and extending around said pulleys and upwardly from the supporting member, power operated driving hammers for the implements arranged to be reciprocated on the second mentioned elements, and means connected with one of the digging implements for swinging it relative to the other.

11. In an excavating machine, the combination of a pair of pivotally connected 70 buckets, relatively movable supporting devices for the buckets on which they are mounted to swing, fluid pressure operated driving means for one of the buckets carried by the supporting devices therefor, means 75 for swinging the buckets to closed position and means for opening the buckets.

12. In an excavating machine, the combination of a pair of pivotally connected buckets, relatively movable supporting devices for the buckets on which they are mounted to swing, fluid pressure operated 80 hammers on said devices arranged to deliver a succession of blows directly to the buckets, means for swinging the buckets to closed 85 position and means for opening the buckets comprising a lever pivotally mounted on one of the buckets and arranged to cooperate therewith to move said bucket to open position, and operating means for said lever.

13. In apparatus of the class described, the combination of a pair of pivotally connected buckets, relatively movable supporting devices on which the buckets are mounted to swing, a fluid pressure operated hammer for one of the buckets carried by the supporting device therefor, a lever pivotally mounted on one of the buckets, an abutment on said bucket with which the lever is adapted to cooperate to effect movement of the bucket from a closed to an open position, and means for operating the lever.

14. In apparatus of the class described, the combination of a pair of pivotally connected buckets, relatively movable supporting devices on which the buckets are mounted to swing, fluid pressure operated driving hammers for the buckets carried by said supporting devices, means for raising and swinging the buckets to closed position, a lever 11 pivotally mounted on one of the buckets, an abutment on said bucket with which the lever is adapted to cooperate to effect opening of the buckets when the lever is swung in one direction, and operating means for the lever.

15. In apparatus of the class described, the combination of a pair of pivotally connected buckets, relatively movable supporting devices on which the buckets are mounted to swing, a fluid pressure operated hammer for

one of the buckets carried by the supporting device therefor, a lever pivotally mounted on one of the buckets, an abutment on said bucket with which the lever is arranged to cooperate to effect movement of the bucket from a closed to an open position, means for operating the lever, and a part on one of said supporting devices arranged to cooperate with the operating means to limit the extent 10 of movement of said bucket when swinging to open position.

16. In apparatus of the class described, the combination of a pair of pivotally connected digging implements, relatively movable supporting devices on which the implements are mounted to swing to and from open position, a power operated hammer for one of the implements mounted on the supporting device therefor, means for moving the implements to closed position, means for moving the implements to open position, including relatively movable cooperating parts on one of the implements, an operating member for one of said parts and means on one of said supporting devices arranged to cooperate with said operating member to limit the extent of movement of the implements when moving to open position.

17. In apparatus of the class described, the combination of a pair of swingingly mounted buckets, members on which the buckets are mounted to swing extending upwardly therefrom, a supporting part for each of said members having a limited sliding movement thereon, means connecting said parts permitting one to swing relative to the other, anvils on said buckets, fluid pressure operated hammers each arranged to deliver a succession of blows to one of the anvils, means connected 40 with the buckets for moving them to closed position, a pair of levers pivotally mounted on one of the buckets, abutments on said bucket with which the levers are arranged to cooperate to effect opening of the buckets, a cable 45 operatively connected with the levers, an abutment on the cable and means on one of the supporting parts arranged to cooperate with the abutment on the cable to limit the extent of movement of the buckets when 50 swinging to open position.

18. In apparatus of the class described, the combination of a pair of pivotally connected digging implements, a support for each implement including a part pivotally connected therewith and an additional part having a limited sliding movement upon said pivoted part, a head connecting said additional parts one of which parts is pivoted upon the head, and means connected with the implements 55 and the head for raising and lowering the same.

19. In apparatus of the class described, the combination of a pair of pivotally connected digging implements, a support for each implement including a part pivotally connected

therewith and an additional part having a limited sliding movement upon said pivoted part, a head connecting said additional parts one of which parts is pivoted upon the head, and power operated driving means for one of the implements carried by the support there- 10

20. In apparatus of the class described, the combination of a plurality of pivotally connected digging implements, supports upon which the implements are pivotally mounted, connecting means for the supports permitting one to move relative to the other, power operated driving means for one of the implements mounted upon the support therefor, and means for raising and lowering the implements. 75

21. In apparatus of the class described, the combination of a plurality of digging implements connected for movement one relative to another, relatively movable supporting devices for said implements on which the latter are arranged to swing, one of the implements having a portion forming an anvil, a power operated driving member on the supporting device for the last mentioned implement arranged to deliver a succession of blows to the anvil, and means for raising and lowering said supporting devices and the implements connected therewith. 85

22. In apparatus of the class described, the combination of a plurality of pivotally connected digging implements, supports upon which the implements are pivotally mounted, connecting means for the supports permitting one to move relative to another, power operated driving means for one of the implements mounted upon the support therefor, means for raising and lowering the implements, and means connected with one of the implements for moving it in a direction away from another. 95
